[57] CLAIM

The ornamental design for a target, substantially as shown and described.

DESCRIPTION

FIG. 1 is a perspective view of the ornamental design for a target in accordance with my invention, with a portion of the target face broken away to allow illustration of the interior of the housing;

FIG. 2 is a front elevational view of the target;

FIG. 3 is a side elevational view of the target;

FIG. 4 is the opposite side elevational view of the target;

FIG. 5 is a rear view of the target;

FIG. 6 is a top plan view of the target;

FIG. 7 is a bottom plan view of the target; and

FIG. 8 is a generally rear perspective view of the target.
